UNITED STATES PATENT OFFICE.

OTTO SCHELL, OF NEW ULM, MINNESOTA.

ATTACHMENT FOR BEER-COOLERS.

SPECIFICATION forming part of Letters Patent No. 703,481, dated July 1, 1902.

Application filed December 30, 1901. Serial No. 87,720. (No model.)

To all whom it may concern:

Be it known that I, OTTO SCHELL, a citizen of the United States, residing at New Ulm, in the county of Brown and State of Minnesota, have invented certain new and useful Improvements in Attachments for Beer-Coolers, of which the following is a specification.

My invention relates to improvements in an attachment for beer-coolers, its object being to provide means for treating the wort after it has been boiled with hops or other material to give it the desired aroma. This I accomplish by means of a hop-receptacle arranged within the feed-pipe leading to the cooler, whereby all the wort after being boiled must pass through said receptacle on its way to the cooler. I preferably construct said hop-receptacle to take the place of the ordinary hop-jack and also provide means in connection with the receptacle for forcing any beer left in the receptacle from the same to the cooler.

To this end my invention consists in the construction and combination hereinafter specifically described and claimed.

In the accompanying drawings, forming part of this specification, Figure 1 is a front elevation of a cooler, showing my invention arranged in connection therewith. Fig. 2 is an end elevation of the cooler. Fig. 3 is a side elevation of my hop-receptacle and the supporting-framework therefor, and Fig. 4 is a section on line $x-x$ of Fig. 3.

In the drawings, A represents an ordinary construction of beer-cooler, consisting of a series of horizontal pipes 2, supported in the framework 3. The top of the framework is provided with a beer-trough 4, from which the beer passes downward on the outside of the series of pipes 2, which are kept filled with cold water for cooling the beer as it passes over them. Arranged below the series of pipes is a trough or tray 5 to receive the beer after it has passed from the cooler. Arranged adjacent to the cooler is a hop-receptacle B, pivotally supported by means of the trunnions 6 in a frame 7, preferably portable. The receptacle at its top is provided with a removable cover 8, held in closed position by means of clamps 9, which fit over the outwardly-projecting flanges 10 and 11 of the cover and receptacle-wall, respectively, as shown in Fig. 4. The top of the cover 8 is

formed with a neck 12, to which is secured the end of a pipe 13 by means of the union 14, said pipe 13 leading to the brewing-kettle D. 55 The receptacle is preferably cylindrical and the cover 8 in the opposite end of the receptacle partly rounded, as shown. Leading from the lower end of the receptacle is a pipe 15, discharging into the trough 4 at the top of the 60 cooler and provided with a drain-cock 16 and preferably with a valve 22 to regulate the flow over the cooler. Within the hop-receptacle B is arranged an open-work chamber or receptacle C of similar shape, but smaller 65 than the outer receptacle, so as to leave an intermediate surrounding space. The inner open-work receptacle C is formed with feet 17, by means of which it is held separated from the bottom of the outer receptacle. An 70 open-work cover 18 is provided which fits over the top of the inner receptacle C and is provided with a neck 19 to fit into the neck 12 of the outer receptacle, as shown in Fig. 4. In order to force all of the wort from the hop-receptacle to the cooler, I provide a pipe 20, connecting the pipe 13 with a source of compressed-air supply (not shown) and provided with a regulating-valve 21. 75

In use the inner open-work receptacle C is 80 partly filled with hops and the covers of the inner and outer receptacles then secured in closing position, as shown in the drawings. With the parts in this position the inlet-pipe 13 leads from the brewing-kettle to the hop-receptacle and the pipe 15 leads from the bottom of the hop-receptacle to the top of the cooler. All the wort passing from the brewing-kettle into the receptacle will percolate 85 through the hops and through the open-work receptacle to the surrounding space, from whence it will be forced by the inflowing wort through the outlet-pipe 15 to the beer-cooler. It will then pass over the cooler in the ordinary manner. The hop sediment, which leaves the 90 brewing-kettle with the wort, will be strained from the beer by the inner open-work receptacle B, thus dispensing with the use of the ordinary hop-jack. When the wort ceases 95 flowing from the brewing-kettle to the hop-receptacle, the wort which remains in said receptacle is forced from the same to the cooler by opening the valve 21 and admitting compressed air. 100

It will be seen that the hop-receptacle is included within and practically forms an enlargement of the pipe leading from the brewing-kettle to the cooler. Thus all of the wort which passes to the cooler must pass through the hops, and can thus be given a uniform flavor.

I claim—

1. The combination with a beer-cooler, a distributor extending along the entire length and above the top thereof, and a kettle arranged above the level of said distributor, of an upright closed receptacle for hops standing alongside said cooler and below said kettle and distributor, a perforated portion within said receptacle and adjacent to the lower end thereof, an inlet-pipe leading from the kettle into the upper end of said receptacle, an outlet-pipe leading from the space between 15 said perforated portion and the adjacent wall of the receptacle upward to the distributor, the arrangement being such that all of the wort is passed from said kettle through said receptacle under pressure to said cooler.
2. The combination with a beer-cooler, a distributor along the top thereof, and a kettle, of a closed receptacle for hops standing alongside said cooler below said kettle, an open-work inner chamber arranged within said receptacle, a conduit leading from said kettle to the top of said receptacle and opening into the receptacle within said open-work chamber, and a conduit leading from the receptacle outside said open-work chamber to said distributor.
3. The combination with a beer-cooler, a distributor extending along the top thereof, and a boiling-kettle, of an upright closed receptacle for hops standing alongside said cooler and below said kettle, an open-work chamber arranged within said receptacle and

interspaced from the bottom thereof, a conduit connecting said kettle with said receptacle, said conduit opening into the upper end of said open-work chamber, and a conduit leading from the lower end of said receptacle outside said open-work chamber to said distributor, whereby all of the wort is passed from said kettle to said receptacle under pressure to said cooler.

4. The combination with a beer-cooler and brewing-kettle, of a closed receptacle for hops arranged alongside said cooler and below said kettle, an open-work chamber arranged within said receptacle, a conduit connecting the kettle with the interior of said open-work chamber, a pipe opening into said conduit for the purpose of admitting air thereto, and a conduit leading from the lower end of said receptacle outside said open-work chamber to the 60 cooler.

5. The combination with a beer-cooler, and a kettle arranged above the same, of a closed receptacle for hops arranged alongside said cooler below said kettle, an open-work hop-retainer within said receptacle, said retainer being interspaced from the bottom of the receptacle, a detachable cover for the upper ends of said receptacle and retainer, a conduit connecting said kettle and cover and opening into said retainer, a conduit leading from the bottom of said receptacle outside said retainer upward to the upper portion of the beer-cooler, and a pivotal support for said receptacle.

In testimony whereof I affix my signature in presence of two witnesses.

OTTO SCHIELL.
